COMMUNICATION CODING AND DECODING APPARATUS

Burton R. Lester, Baldwinsville, N. Y., assignor to General Electric Company, a corporation of New York

Application October 1, 1952, Serial No. 312,516

5 Claims. (Cl. 340—345)

My invention relates to communications systems, and more particularly, to such systems in which stereotyped messages to be communicated between selected stations are preliminarily encoded and transmitted as a pulse-modulated carrier, to a distant receiver at which the coded message is detected and decoded to provide a visual indication of the message.

An object of the invention is to provide a novel communications system in which a considerable reduction in transmitter time can be effected by coding individual messages of a selected group of stereotyped messages and then transmitting only the code designation of the message.

Another object of the invention is to provide a communications system of the type referred to, wherein the received messages are displayed for visual observations, whereby the time required for receiving is only long enough to place into operation a decoding mechanism.

A further object of the invention is to provide a communications system of the herein-mentioned type in which the receiving apparatus and the transmitting apparatus are substantially identical, and further wherein the apparatus for coding the message can be used, without modification, for decoding the received message.

Still another object is to provide a system of the type mentioned having pulse-transmitting means and pulse-receiving means and means operable on the actuation of said transmitting means to render inoperative said receiving means throughout the period of pulse transmission.

Yet another object is to provide a novel and improved coding and decoding mechanism having a first part operable to translate data in a decimal form into a binary digital representation and a second part operable to translate data in binary digital form into a decimal form, said mechanism including means for rendering said first part inoperative throughout the period of operation of said second part.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings in which

Figs. 1a and 1b, read in side by side relation, illustrate a complete transmit-receive station according to the invention, and

Fig. 2 is a diagram representing a sequence in the binary system of numeration employed in the coder-decoder apparatus of the invention.

A communication system according to this invention may comprise a plurality of transmit-receive stations, each station being identically constituted and adapted to transmit and receive, at any given instant, a selected one of a plurality of predetermined or stereotyped messages. The system can be generally employed whenever and wherever it is required to transmit a large number of

2

such messages to a number of individual receivers, and in one practical embodiment, one such station was located on the ground, and other stations were mounted in aircraft providing a communication, navigation, traffic control and ground-to-air transmitting link. Such a link, it will be noted, is capable of sending both information and control signals to one or more aircraft within the line of sight of one radio-frequency channel.

For the purpose of simplifying the present description, 10 the number and types of stereotyped messages that can be transmitted and received has been arbitrarily reduced to indicate generally the scope of the apparatus without unnecessarily burdening the description with repetitive details. Thus, in the description that follows, it will be considered that information concerning "bearing" and "elevation" only are desired to be transmitted and that for each type of information there are 256 different predetermined messages than can be sent. It will, of course, be understood that these types and numbers of messages are 15 exemplary only and that other types and numbers can be employed, as for example, distance, temperature, and related data as well as a variety of commands and orders such as "Report," "Repeat," "Identify," etc.

In Figs. 1a and 1b, a transmit-receive station is shown 20 comprising an oscillator 11, shown in the lower left-hand corner of Fig. 1a, which may be of any suitable conventional type for producing radio-frequency oscillations at a desired frequency value. The oscillator 11 is adapted to be keyed by a modulator 13, which may also be of any 25 suitable conventional variety to cause the emission by oscillator 11 of positive and/or negative pulses at a suitable rate, say from 20 to 30 pulses per second, over a bandwidth of from 200 to 300 cycles per second. A train of pulses including, in the illustrated embodiment, 10 equi-amplitude equi-duration and equi-spaced pulses of positive and/or negative polarity, carries the message or intelligence to be transmitted coded in binary form, and such a train is applied to an antenna (not shown) by means of transmission line 15. Similar trains of pulses, 30 radiated from another station, after reception by the antenna, are fed to receiver and detection apparatus 17 for subsequent decoding and visual presentation.

The elements of my coder-decoder apparatus by means 35 of which the message or intelligence to be transmitted is coded in binary form preliminarily to actuation of the modulator 13, and which also functions to decode the received pulse train to yield the intelligence conveyed thereby, will now be described in detail.

The coder-decoder apparatus comprises four coding- 40 wheel assemblies CW_I, CW_{II}, CW_{III}, CW_{IV} which are identically constructed and operate in identical fashion to translate data, information or intelligence of any type or form into a binary digital form and conversely to translate such data, information or intelligence in binary 45 digital form into its original form. The assemblies CW_I and CW_{II}, in the illustrative embodiment, are for accommodating intelligence of the first type, say elevation, and assemblies CW_{III} and CW_{IV} are for accommodating intelligence of the second type, say bearing. Additional assemblies can, of course, be provided where it is desired to accommodate additional types of intelligence.

As noted, the coder-wheel assemblies are identical in construction and in mode of operation. Accordingly, the construction of one such assembly, say assembly 50 CW_I, will be described in detail, it being understood that the corresponding elements of the other assemblies are similarly constructed for similar operation.

Coder-wheel assembly CW_I comprises an array of rotatable cams C₁, C₂, C₃ and C₄ mounted for conjoint 55 rotation on a common shaft 19 which also carries a ratchet 21 of a stepping switch 23. The stepping switch 23 can be of any suitable type well known

in the art and having a movable core 12 that carries a pawl 14 in engagement with the ratchet 21 so that, when the winding is energized, the core 12 is drawn downward against the action of a spring carrying the pawl into engagement with the next tooth of the ratchet 21. The downward movement of the core also opens interrupter contacts, subsequently to be described, thereby breaking the energizing circuit of the winding. The core is thereupon returned to its unattracted position by means of the spring 16, causing the pawl 14 to notch or step the ratchet 21 one step. Cam C₁ is formed with eight equi-angularly spaced high portions as at 25 and an equal number of equi-angularly spaced low portions as at 27 interspersed between the high portions 25. Cam C₂, adjacent cam C₁ is formed with one half the number or four high and low portions, and cams C₃ and C₄ are respectively similarly formed with half the number of high and low portions of the cams next adjacent thereto. Associated with each cam are respective spring-biased cam followers 29, 31, 33 and 35 each of which carries a pair of contactors, as at 37 and 39 for actuating respective pairs of contacts 41, 43 and 45, 47. It will be noted that one contact of each pair of contacts is normally open and the other is normally closed.

The coder-wheel assemblies CW_{II}, CW_{III} and CW_{IV} are similarly constituted of identically arranged sets of cams, identified as cams C₅, C₆, C₇ and C₈ in assembly CW_{II}; C₉, C₁₀, C₁₁, and C₁₂ in assembly CW_{III}; and C₁₃, C₁₄, C₁₅ and C₁₆ in assembly CW_{IV}.

The stepping-switch and ratchets in the assemblies CW_{II}, CW_{III}, and CW_{IV} are also similar to corresponding elements of assembly CW_I, and these are identified in the drawing by the numerals 24, 26, and 28 referring to the stepping-switches and numerals 30, 32, and 34 referring to the ratchets.

The position of a given cam will, for this description, be regarded as "normal" when the associated follower is on a high portion of the cam and the open or closed condition of the related contacts will be determined accordingly. Thus, in the illustration, cam C₁ is in the "actuated" condition, since the follower 29 is at a low portion 27 of the cam. Hence, the contacts 41 and 45, which are normally open, are presently in closed condition. The cam C₄ is instantly in the normal position.

The arrangement of the high and low portions 25 and 27 on the cams C₁-C₄, is diagrammatically shown in developed form in Fig. 2, in which shaded areas, as at 49, correspond to the high portions 25 and unshaded areas, as at 51, correspond to the low portions 27. The developed representation of Fig. 2 thus consists of four vertical columns 53, 55, 57 and 59 of alternatively spaced shaded and unshaded areas, the column 53 containing eight shaded areas and eight unshaded areas, the column 55 containing four shaded and four unshaded areas, column 57 having half the number found in column 55, and column 59 having half the number found in column 57.

If, in the diagram of Fig. 2, the shaded areas represent zeros and the unshaded areas represent ones, there is thus presented a representation of a binary sequence in which the horizontal rows considered from top to bottom correspond to 0000, 0001, 0010, 0011, etc. corresponding respectively to the decimal numbers 0, 1, 2, 3, etc., shown at the right hand edge of the diagram. The numbers "1," "2," "4," and "8" across the top of the diagram, indicate by the presence of an unshaded area at the intersection of a given row and the respective column, the presence of the corresponding decimal number. Thus, in the row corresponding to decimal 13 or binary 1101, non-shaded areas are found in the "8" column, the "4" column and the "1" column indicating the presence of an 8, a 4, and a 1 in the decimal number, which together make up the decimal 13.

Returning now to Figs. 1a and 1b, it will be seen that the instant setting of the cams C₁-C₄ of coding-wheel

assembly CW_I, with the follower 35 of cam C₄ on a high portion and the followers 31, 33 and 24 of the wheels C₃, C₂ and C₁ on low portions, when interpreted in view of the binary sequence diagram of Fig. 2, corresponds to a binary 0111 or decimal 7, and the decimal number 7 is, accordingly, found on an indicia wheel 61 that is mounted on the cam shaft 19 for rotation with the cams C₁-C₄. Also, it will be observed that when C₁-C₄ are rotated one notch, as by the actuation of the stepping-switch 23, the follower 35 of cam C₄ will have dropped to the low portion of the cam C₄ while the followers 33, 31 and 29 of the cams C₃, C₂ and C₁ will have been raised to high portions of the respective cams, so that the setting of the coding wheel assembly CW_I now corresponds to the binary 1000 or decimal 8.

The description just completed of the construction of coder-wheel assembly CW_I whereby the instant setting of the cams C₁-C₄ corresponds to a predetermined binary number, which in turn is translatable into a corresponding decimal number applies identically to the coder-wheel assemblies CW_{II}, CW_{III} and CW_{IV}, the latter assemblies being of essentially the same form as assembly CW_I.

There follows now a description of the circuit connections of the individual contacts of the cam switches 25 of respective pairs of coder-wheel assemblies, and for simplification of the description, only representative connections will be described, it being clear that the corresponding connections for the remaining cam switches are similarly made.

Thus, turning again to coder-wheel assembly CW_I, and particularly the upper pair of cam actuated contacts 41 and 43, it will be observed that said contacts 41 and 43, here shown actuated, are respectively serially connected to normally closed and normally open relay-operated contacts 63 and 65. The series-connected contacts 41 and 63 are connected in shunt with the series-connected contacts 43 and 65, one side of the shunt arrangement being grounded and the other side being connected, as by conductor 67, to the winding 69 of the stepping switch 23.

The contacts 63 and 65 are actuatable by means of an electromagnetic relay R₁, which as shown, is the extreme right-hand one of a bank of eight similar electromagnetic relays R₁-R₈, which function as data storage devices employed in the message-reception phase of the transmit-receive station of this invention. Each relay of the bank R₁-R₈ is provided with a winding, as at 70 for relay R₁, which upon energization, operates to actuate a pair of relay contacts associated with the uppermost pair of cam contacts of each of a pair of cam elements in the coder-wheel assemblies. Thus, relay R₁ controls the actuation of the relay contacts 63 and 65 that are respectively connected to the cam contacts 41, 43 of cam C₁ in assembly CW_I. Relay R₁ also controls the actuation of a second pair of relay contacts 71, 73 that are connected to cam contacts 75, 77 of the cam C₉ in coder-wheel assembly CW_{III}.

For a reason that will become more apparent as the description of the structure and operation of the apparatus proceeds, the uppermost pair of cam contacts of each cam C₁-C₁₆, such as the contacts 41, 43 of cam C₁ and contacts 75, 77 of cam C₉ are termed "sensing contacts" inasmuch as these contacts operate to sense the potential at one terminal of the winding of the associated relay R₁. As shown in the case of relay R₁, for example, one terminal of the winding 70 thereof is connected, as by conductors 79 and 81, through a normally open relay contact 82, to a source of positive potential, conventionally indicated by B+, the other terminal of winding 70 being connected, as by conductor 83, to a tap marked "1" on a scanning switch element S₁ having a movable wiper 84. A holding contact 85 for relay R₁ is connected between the conductor 83 and ground so that, upon impulse energization of relay R₁ by a pulse of positive polarity in a manner subsequently to be described, the contact 85 is made, and if contact 82 is in closed condition, the

relay R_1 is sealed in through a circuit extending from $B+$, through contact 82 , conductors 81 and 79 , winding 79 and contact 85 to ground.

It will be helpful to note for the present that a relay R_{10} shown in the lower left-hand portion of Fig. 1a is provided with a winding 90 one terminal of which is connected to $B+$ and the other is adapted to be connected to ground through the armature 92 of a polarized relay PR . As shown, the winding of the polarized relay PR is adapted for energization by the pulsed output of the receiving apparatus 17 , which as noted above, comprises a pulse train of positive and negative pulses according to the information or intelligence contained in the received message. The relay PR is polarized so that a positive received pulse causes deflection of the armature 92 to the left resulting in the energization of relay R_{10} and the consequent actuation of contact 88 as well as a second contact 94 . A negative received pulse causes deflection of the armature 92 to the right resulting in the energization of a relay R_{11} the energization of which closes a contact 96 , the function of which is subsequently to be described.

Returning now to the bank of relays R_1-R_8 , it will be seen that one terminal of the winding of each relay is connected to a respective tap of the switch S_1 , the taps being appropriately marked "2" for relay R_2 , "3" for relay R_3 , etc., so that as the wiper 84 is stepped around, contact is made successively with the winding of each relay R_1-R_8 , the other terminal of each winding being connected in common, by conductors 79 and 81 , through contact 82 , to $B+$.

Switch S_1 is provided with three additional taps marked "9," "N" and "0," respectively, the "9" and "N" taps being open and corresponding to the "power" stage and "home" or normal position, respectively, of the switch, as will appear. The "0" tap is connected to one terminal of the winding of a message-selector relay R_0 , the other terminal of said winding being connected to the common connection formed by conductors 79 and 81 . Relay R_0 is also provided with a holding contact 98 similar to the holding contacts of the storage relays R_1-R_8 , as exemplified by contact 85 of relay R_1 , and in addition, relay R_0 actuates a pair of contacts 100 and 102 , one of which is normally closed and the other normally open. One side of each of the contacts 100 and 102 are connected jointly, by conductor 104 to the wiper 106 of a power control switch S_2 for the coder-wheel assemblies CW_I-CW_{IV} the wiper 106 and wiper 84 being mounted on a common axis, indicated at 108 , for conjoint rotation. The switch S_2 is provided with a single segmental contact 110 disposed in a position corresponding to the number "9" position of the switch S_1 so that when the wipers 84 and 106 step off the "8" position and on to the "9" position, a circuit is made from $B+$ through normally closed contacts 112 and 114 of a pair of relays R_{10} and R_{16} , respectively, to be described hereinbelow.

The other sides of the contacts 100 and 102 of the message selector relay R_0 are connected to the windings of selected pairs of the stepping switches in the coder-wheel assemblies CW_I-CW_{IV} . Thus, contact 100 is connected in common to windings of stepping switches 23 and 24 of assemblies CW_I-CW_{II} , respectively, the connection being affected through conductors 116 and 118 and normally-closed interrupter contacts 122 and 120 of the switches 23 and 24 , respectively.

Similarly, the contact 102 is connected in common to the windings of stepping switches 26 and 28 of assemblies CW_{III} and CW_{IV} , respectively, these connections being effected through conductors 124 and 126 and normally-closed interrupter contacts 128 and 130 of the switches 26 and 28 , respectively.

The stepping action of wipers 84 and 106 of switches S_1 and S_2 , respectively, is accomplished by means of a master stepping switch arrangement MS , comprising a conventional stepping switch having a winding 109 and a

ratchet 111 , the latter being suitably mounted on the axis 108 to produce rotative movement thereof. In a manner well known to those skilled in the art, energization of the winding 109 from a suitable source, here indicated conventionally by $B+$, causes an armature-pawl 113 to be drawn down a notch of the ratchet compressing a spring so that, upon deenergization of the winding 109 , the pawl is pushed upward stepping the ratchet around one step or notch. The circuit from $B+$ through the winding 109 is completed to ground by means of conductors 115 , 117 , and 137 , and either of the contacts 94 and 96 of relays R_{10} and R_{11} , respectively, depending on which of the two is actuated. It will be recalled that contact 94 is closed in response to a positive pulse and contact 96 is closed by a negative pulse. Thus, pulses of either polarity are effective to close one or the other of the contacts 94 or 96 causing the energization of winding 109 of the master stepping switch MS , which, in turn, produces stepping movement of the ratchet 111 . The step-by-step rotation of the ratchet 111 results in a corresponding movement of the axis 108 and the wipers 84 and 106 , as well as wipers 119 , 121 , 123 and 125 of associated rotary switches S_3 , S_4 , S_5 and S_6 , respectively. As shown, all the wipers are ganged on the axis 108 for conjoint movement in response to stepping or notching of the switch MS .

Since the scanning switches S_3 and S_4 are utilized in the message-transmission phase of the operation of the system, the description of the circuitry associated therewith will be given later hereinbelow.

Switches S_5 and S_6 are "off-normal" contacts, so-called, inasmuch as they provide open contacts when the master stepping switch MS , as evidenced by the position of the wipers 84 , 106 and 119 , is in the normal position N , and provide closed contacts for all other positions of the master switch. To that end, the switches S_5 and S_6 may each be formed with a substantially circular conductive strip 127 and 129 having insulated gaps 132 and 134 , respectively, at positions thereon corresponding to the normal position N .

As shown, off-normal contact S_5 is connected, as by conductor 117 and a conductor 135 across a normally-open relay-operated contact 136 and the shunt pair is connected at one side to $B+$ through the winding 109 of the master stepping switch MS . The same side of the shunt-connected contacts S_5 and 136 is connected to ground, as by conductor 137 , through the contacts 94 or 96 of relays R_{10} or R_{11} , respectively.

The other side of the shunt-connected contacts S_5 and 136 is connected to ground through either of a pair of branched paths, one said path including a series connection of a normally-open relay contact 138 and a normally-closed relay contact 139 . The other path to ground is provided by a series connection of a normally-closed interrupter contact 140 of the master stepping switch MS , a normally-open relay contact 141 and a normally-closed relay contact 142 . Relay contact 141 is operated by a time-delayed operating relay R_{16} having a conventional means, such as a dashpot 146 for delaying the operation of the relay by a predetermined short time interval. Contact 142 is operated by relay R_{18} .

Off-normal contact S_6 is connected, at one side, to $B+$ by conductor 143 through the winding 144 of a relay R_{17} , and on the other side to ground by conductor 145 . The grounded side of the off-normal contact S_6 is also connected, through the normally-open contact 88 of relay R_{10} and conductor 86 , to the wiper 84 of switch S_1 .

To complete the description of so much of the system as is utilized in the reception of a message, it will be noted that the master stepping switch MS is provided with a second interrupter contact 148 which on one side is connected to $B+$ through the winding of the relay R_{16} and to ground through a normally-open contact 150 of relay R_{16} .

in series with normally-open contact 152 of relay R₁₇. The other side of interrupter contact 148 is connected to ground through conductor 154 and a series connection of normally-closed second interrupter contacts 156, 158, 160 and 162 of the stepping switches 26, 28, 24 and 23, taken in that order.

The operation of the receiving portion of the system described to this point can now be explained with reference to a received message. As noted above, a message consists of 10 pulses each of which can be positive or negative according to the intelligence contained therein. Also, the polarized relay PR is poled to effect energization of relay R₁₀ in response to the reception of a positive pulse and to effect energization of relay R₁₁ in response to reception of a negative pulse.

In the quiescent period, before the reception of any pulse, only the winding of relay R₁₆ is energized, the energization thereof being effected by the circuit extending from B+, the winding of relay R₁₆, interrupter contact 148 of the master stepping switch MS, conductor 154, and the interrupter contacts 156, 158, 160 and 162 of the coder-wheel assembly stepping switches. All the other relays and all the stepping switches are de-energized, and all the wipers of the switches S₁-S₆ are on the normal position N.

Now, if a pulse of either polarity is received, so that either contact 94 or contact 96 is closed, winding 109 of the master stepping switch MS is energized through conductors 115, 117 and 137, and at the termination of the pulse, the ratchet 111 is stepped one notch moving all the wipers off the normal position N, wiper 84 of switch S₁ contacting the 0 tap, and wipers 123 and 125 contacting the segments 127 and 129, respectively, thus closing the off-normal contacts S₅ and S₆. The closing of contact S₅ results in the energization of relay R₁₇ and the opening of the interrupter contact 148 results in the deenergization of R₁₆.

In the interval between the termination of the first pulse and the reception of a second pulse, winding 109 of switch MS is deenergized and the interrupter contact 148 is again closed by the upward thrust of the armature-pawl 113, again energizing the winding of relay R₁₆. But, as noted, relay R₁₆ is delayed a short time interval in its operation by the dashpot 146, so that its contacts are not instantly closed. Thus, if a second pulse is received before the contacts of relay R₁₆ are closed, the switch MS is stepped a second notch thereby in exactly the same manner as just described.

However, it may happen that the first pulse received is merely a random noise pulse and not followed by a second pulse and successive pulses in regular order and timing. In that case, assuming no pulse is received after the first by the time that relay R₁₆ has operated to close the contact 150, the reenergization of relay R₁₆ results in the sealing in of the relay R₁₆ through the closed contact 150 and the actuated contact 152 of relay R₁₇. Then, since contact 141 of relay R₁₆ and off-normal contact S₅ are both closed, the master stepping switch MS is interruptedly operated through its interrupter contact 140 and the normally-closed contact 142 of relay R₁₈ until the switch MS steps around to the normal position N whereupon the off-normal contacts S₅ and S₆ open de-energizing the winding 109 of switch MS and the winding 144 of relay R₁₇. The operation of the relay R₁₆ results in the breaking of contact 114 removing B+ from the windings of the stepping switches 23, 24, 26 and 28, thus assuring that the coder wheel assemblies do not operate as the master stepping switch MS steps around to its home position N after the reception of a random noise pulse. The mode of operation in response to a random noise pulse has proved to be very useful in eliminating spurious and erroneous indications and accordingly constitutes an important aspect of the system.

Where the first pulse, which it will be observed, is preparatory only and serves (1) to step the master switch

MS off the normal position, (2) to deenergize relay R₁₆ and (3) to energize relay R₁₇, is followed by a second pulse before the time delay period of relay R₁₆ has expired, relay R₁₆ is not sealed in, but instead the interrupter contact 140 is broken before relay R₁₆ becomes re-energized. All the received pulses in the sequence, since they are spaced less than the time delay period, operate thus to step the switch MS one notch. However, only positive pulses that actuate relay R₁₀ cause the closing of contact 88 of relay R₁₀ which is connected to the wiper 84 of switch S₁. So, as the wiper 84 steps around contacting the taps 0-8 that are connected respectively to the windings of the relays R₀-R₈, certain ones of these relays are sealed in by the positive pulses while those other relays receiving negative pulses remain unsealed and unenergized.

The second pulse in the received message determines the type of message that is being received. For example, if the second pulse is positive, the message selector relay R₀ is energized and sealed in through its holding contact 98. Also, contact 100 is closed, so that upon the subsequent closing of contact S₂, the stepping switches 23 and 24 of coder assemblies CW_I and CW_{II} are energized, corresponding to information concerning bearing. If the second pulse is negative, relay R₀ is unaffected and not sealed in. Thus, contact 102 is closed, and, on the closing of switch S₂ the stepping switches 26 and 28 of coder-wheel assemblies CW_{III} and CW_{IV} are energized yielding elevation information.

The remaining eight pulses of the received train of pulses contain the stereotyped message, and cause the master stepping switch MS to step around through the remaining 8 positions, e. g. to the open position "9" of the S₁ switch, various ones of the relays R₁-R₈ being energized and sealed in, and others being unenergized and not sealed in according to the polarity of the successive pulses. When the switch MS reaches the "9" position, the power control switch S₂ is closed by the contacting of wiper 106 and segment 110, connecting the selected pair of coder wheel assemblies CW_I and CW_{II} or CW_{III} and CW_{IV} to B+ through the closed contacts 112 and 114, conductor 104, either one of the contacts 100 or 102, and the conductors 116 and 118 or the conductors 124 or 126.

The stepping switches of the selected coder wheel assemblies then step around, by means of the interrupter contacts in series with the respective windings, driving the associated cams, until the position of the cam switches is attained for which the connection to ground is broken by the cam contacts.

When each of the stepping switches of the selected coder-wheel assemblies comes to rest with the respective interrupter contacts closed for a period greater than the time-delay period of the relay R₁₆, the latter is then operated and sealed in through the contact 152 of relay R₁₇, whereupon the master stepping switch MS steps one more notch to home or normal position N, being energized through the off-normal contacts S₅, the interrupter contact 140, and the contacts 141 and 142 of relays R₁₆ and R₁₈, respectively. At the home position N, the opening of off-normal contact S₆ deenergizes the relay R₁₇ and stops the master stepping switch MS. Also, the opening of contact 82 of relay R₁₇ removes B+ from the relays R₀-R₈ and unseals them. The instant position of the two selected coder-wheel assemblies then corresponds to the intelligence contained in the received message.

In the transmission of a message by the apparatus of my invention, a pair of coder-wheel assemblies is preliminarily selected according to the type of message sought to be sent. The cams of the selected pair are then manually rotated, as by manipulation of the indicia wheel 61, for example, until the desired position of the cams is attained corresponding to the message. This rotation sets the various contacts associated with the cams corresponding to the contacts 45 and 47 of cam C₁ in coder-wheel

assembly CW_1 . Thus, for transmission, the lower-most pair of contacts associated with each cam C_1-C_{16} are employed. And, as noted hereinabove, these contacts are interconnected through the switches S_3 and S_4 of the master stepping switch MS .

A more complete description of the switching and relay elements employed in the transmission operation will now be given. Again, since the connections of the individual contacts of the respective cams C_1-C_{16} are similar and symmetrical, for simplicity, the description of the connections of the contacts 45 and 47 of cam C_1 will be taken as illustrative of all the other connections.

One of the pair of contacts presently concerned is normally open the other being normally closed. As shown, cam C_1 is in the actuated condition since, as noted above, the follower is at a low 27 on the cam. Thus, the normally-open contact 45 is shown closed and the normally closed contact 47 is shown open.

One side of each of the contacts 45, 47 is connected, in common, by conductor 164 to tap "1" of the switch S_3 , the other side of contact 45 being connected, by conductor 166 to the negative bus 168 of a source of modulating voltage, while the other side of contact 47 is connected to the positive bus 170 of the source.

The lower-most pairs of contacts associated with cams C_2-C_8 are similarly interconnected to the buses 168, 170 and to the taps "2" through "8" respectively of the switch S_3 . Tap "9" of switch S_3 is open and taps "N" and "0" are connected respectively to negative bus 168 and positive bus 170. The connection of the "0" tap to the positive bus insures the provision of a positive pulse in the second pulse position of the train indicating the message type corresponding to coder-wheel assemblies CW_I and CW_{II} .

The lower-most pair of normally open and normally closed contacts of cams C_9-C_{16} are connected to the buses 168 and 170 and to the taps "1" through "8," respectively of the switch S_4 in a manner similar to that described above. Tap "9" of switch S_4 is open and taps "N" and "0" thereof are each connected to the negative bus 168. The connection of the "0" tap of switch S_4 to the negative bus ensures the provision of a negative pulse in the second pulse position of the train indicating the message type corresponding to coder-wheel assemblies CW_{III} and CW_{IV} .

The wiper 119 of switch S_3 is connected to the modulator 13 by conductor 172, through normally-open contacts 174 and 176 of a pair of relays R_{20} and R_{22} , respectively, and a normally-closed contact 178 of a time-delay operate relay R_{21} of which the time-delay operation is conventionally illustrated by the dashpot device 180.

The wiper 121 of switch S_4 is connected to the modulator 13 through conductor 182, a normally-open contact 184 of relay R_{23} , conductor 186, and the contacts 174 and 178.

A pair of pushbutton switches P_1 and P_2 actuating contacts 188, 190 and 192, 194, respectively, are shown in the lower left-hand portion of Fig. 1a, either of which, when momentarily closed, initiates the transmission process. One side of each of the contacts 188-194 is connected to ground through a normally-closed contact 196 of relay R_{17} . Contact 190 of button P_1 and contact 194 of button P_2 are jointly connected through the winding of relay R_{18} to $B+$. Contact 188 of button P_1 is connected to $B+$ through the winding of relay R_{22} , and contact 192 of button P_2 is connected to $B+$ through the winding of relay R_{23} . Contact 192 is also connected to ground through a normally-open contact 197 of relay R_{23} in series with a normally-open contact 198 of relay R_{17} .

The winding of relay R_{19} is connected between $B+$ and ground through a pair of branched paths one of which includes a normally-open contact 200 of relay R_{18} , the other path being provided by a series connection of normally-open contacts 202 and 204 of relays R_{17} and R_{19} , respectively.

The winding of the time-delay release relay R_{20} is connected between $B+$ and ground by a series circuit of a normally-open contact 205 of relay R_{19} and a normally-closed contact 208 of relay R_{21} .

5 The winding of the time-delay operate relay R_{21} is connected between $B+$ and ground through a normally-open contact 210 of relay R_{20} .

Relay 19 actuates an additional normally-closed contact 212, which, as shown, is in the line feeding the input circuit to the receiver and detection apparatus 17 to disconnect the same during the transmission process.

In the transmission of a message, and assuming that the indicia wheels have been rotated to the indicated portions (each displaying a decimal 7), the closing of pushbutton P_1 causes information in the coder-wheel assemblies CW_I and CW_{II} to be transmitted. The button P_1 should be held closed long enough for the master stepping switch MS to step away from the home or normal position N . The sequence of operation will now be described.

Relays R_{18} and R_{22} are momentarily energized through the normally-closed contact 196 of relay R_{17} , and contact 136 of relay R_{18} , in closing, shunts the off-normal contact S_5 . Also, when contact 200 of relay R_{18} closes, 25 relay R_{19} is energized, which by the closing of its contact 206 results in the energization of relay R_{20} . The closing of contact 174 of relay R_{20} and contact 176 of relay R_{22} results in the application of a negative voltage from the N position of switch S_3 to the modulator 30 13 through the conductor 172 and contacts 176, 174 and 178 to form the first output pulse.

The closing of contact 138 of relay R_{20} also results in the energization of the winding 109 of the master stepping switch MS through contact 136 of relay R_{18} , contact 138 of relay R_{20} and contact 139 of relay 35 21, so that the switch MS steps one notch to the "0" position of switch S_3 .

As soon as the switch MS steps from the home position N , relay R_{16} is deenergized by the breaking of interrupter contact 148; the off-normal contact S_6 closes causing energization of relay R_{17} through the circuit including conductors 143 and 145. Relay 17 actuates contacts 202 and 198 thereof, sealing in relays R_{19} and R_{22} , respectively.

45 All the foregoing operations take place in a relatively brief time interval and, as mentioned above, pushbutton P_1 may be released as soon as the master stepping switch steps off the home or normal position N . Release of the button P_1 causes relay R_{18} to drop out since the latter is not sealed in. The first output or preparatory pulse is terminated by the operation of the time-delay operate relay R_{21} , which is energized and operated a brief interval after the closing of contact 210 of relay R_{20} . The operation of relay R_{21} also opens normally-closed contact 139 thereof thereby deenergizing the winding 55 109 of the master stepping switch MS placing the latter in readiness to be stepped again.

After a brief release delay from the time that relay R_{21} operates, relay R_{20} is deenergized by the opening of normally-closed contact 208 of relay R_{21} , relay R_{21} is deenergized due to the opening of the normally-open contact 210 of relay R_{20} , and relay R_{20} is reenergized because of the closing of normally-closed contact 208 of relay R_{21} . Thus, the modulator 13 is again supplied with a voltage, this time a positive pulse from tap "0" of switch S_3 through conductor 172, contacts 176, 174 and 178, indicating the message to follow is of the type characterized by coder-wheel assemblies CW_I and CW_{II} . This pulse is terminated upon the operation of the time-delay operation relay R_{21} opening its normally-closed contact 178. The second pulse, being positive operates to seal in the relay R_0 on the receiving station routing the message to the S_3 switch thereof and to the coder-wheel assemblies CW_I and CW_{II} .

75 The cycle of pulse transmission and stepping con-

tinues as described, each pulse transmitted being of polarity depending upon the setting of the corresponding pair of lowermost contacts, such as the contacts 45 and 47 of cam C₁, which as described above, is controlled by the setting of the coder-wheel assemblies.

It will be noted that if push button P₂ had been actuated, the second pulse would have been negative in polarity, the "0" tap of switch S₄ being connected to the negative bus 168. Such a negative second pulse has no effect on relay R₀ in the receiving station resulting in the routing of the message to the switch S₄ thereof and thence to the coder-wheel assemblies CW_{III} and CW_{IV}. Otherwise, the operation of transmission from the assemblies CW_{III} and CW_{IV} through the contact 184 of relay R₂₃ instead of the contact 176 of relay R₂₂ is the same as described in connection with the assemblies CW_I and CW_{II}.

The stepping of switch MS continues until switch MS reaches home position, whereupon the off-normal contact S₆ opens deenergizing winding 144 of relay R₁₇ breaking contact 152 thereof. Relay R₁₆ is again energized through the interrupter contact 148 of the switch MS and the interrupter contacts 156, 158, 160 and 162 of the coder-wheel stepping switches 26, 28, 24 and 23, respectively, and the apparatus is again ready to receive or transmit a message.

It is to be noted particularly that when relay R₁₈ is energized by pushing one or the other of the buttons P₁ or P₂, the normally-closed contact 142 thereof opens so that the winding 109 of the master stepping switch MS is not at first energized through the interrupter contact 140 thereof, but rather through the contacts 139 and 138 of relays R₂₁ and R₁₈, respectively, and contact 136 of relay R₁₈. Thus, when the switch MS steps off the home position N, and energizes relay R₁₇ through the off-normal contact S₆, relay R₁₉ is then sealed in through contact 202 of relay R₁₇ and contact 204 of relay R₁₉. Relay R₁₉ is thus held in during the entire transmitting operation, and by the opening of normally-closed contact 212 thereof, the amplifier 17 is isolated from the transmission line 15 so that transmitted signals are not fed back to the transmitting apparatus.

Also, during the entire transmission period, the normally-closed contact 112 of relay R₁₉, being then in open condition, isolates from B+ the operating windings of the stepping switches 23, 24, 26 and 28 of the coder-wheel assemblies so that they are maintained deenergized. Absent such an isolation contact, the coder-wheel stepping switches would tend to position themselves to correspond to the deenergized relays R₀-R₈ when the master switch MS reached the "9" position.

It will be observed further that the ground connection from pushbuttons P₁ and P₂ is made through normally-closed contact 196 of relay R₁₇. Accordingly, transmission of a message cannot be commenced except when the switch MS is in the normal position N when relay R₁₇ is deenergized. In this manner, transmission of a message is prevented during the time that the switch MS is stepping around to normal or home N as a result of a random noise pulse or during the reception of a message.

The width and spacing of the transmitted pulses, it will be noted, are determined accurately and solely by the time delay periods of the relays R₂₁ and R₂₀ of which the normally-closed and normally-open contacts 178 and 174, respectively, are in series circuit with the input of the modulator 13. The pulse width and spacing is thus equal to the respective periods of time during which the relays R₂₀ and R₂₁ are simultaneously energized and deenergized.

While I have illustrated and described particular embodiments of my invention, it will, of course, be understood that various changes and modifications may be made, and I contemplate by the appended claims to cover all such changes and modifications as fall within the true spirit and scope of my invention.

What I claim as new and desire to secure by Letters Patent of the United States is:

1. A data translation apparatus, comprising a plurality of sets of cam surfaces, a plurality of cam actuated sets of complementary contact members operatively associated with said cam surfaces, motive means drivingly connected to produce relative motion between said cam surfaces and said cam actuated contact members, said cam surfaces being movable independently of said motive means, data storage apparatus, means including a first group of said contact members and said motive means for driving said cam surfaces to a position governed by entries in said data storage apparatus, a scanning switch means including said scanning switch and a second group of said contact members operable in complementary fashion with respect to said first group of contact members for transmitting a train of electric impulses characterizing the relative position of said cam surfaces and said cam actuated contact members, and means for preventing movement of said cam surfaces by said motive means during the operation of said scanning switch.

2. A data translation apparatus comprising data storage apparatus accommodating a plurality of entries, a scanning switch having a normal position, means connecting said scanning switch between an information input channel and said data storage apparatus, a stepping motor for driving said scanning switch in response to signals present in said input channel, a relay operable after a time delay greater than a step cycle of said stepping motor connected in an energizing circuit including contacts closed when said stepping motor is de-energized, a contactor closed when said scanning switch is off normal situated in the energizing circuit for said stepping motor, a holding circuit for said relay opened when said scanning switch returns to normal, and contacts controlled by said relay connected in the energizing circuit for said stepping motor in series with said off normal contactor.

3. In data translation apparatus, a first group of movable cam surfaces, a second group of movable cam surfaces, first motive means connected with said first group of cam surfaces, second motive means connected with said second group of cam surfaces, a first group of contactors actuated by said first group of movable cam surfaces, a second group of contactors actuated by said second group of movable cam surfaces, data storage apparatus, first, second and third scanning switches having a normal position, means connecting said first scanning switch between a communication channel and said data storage apparatus, third motive means for driving said scanning switches, means including a source of electric energy and said second scanning switch for impressing signals controlled by said first group of contactors on said communication channel, means including a source of electric energy and said third scanning switch for impressing signals controlled by said second group of contactors on said communication channel, means responsive to signals arriving over said communication channel for energizing said third motive means, means operable independently of said communication channel for energizing said third motive means and preventing influence of the operation of said third motive means by signals on said communication channel, means for preventing influence of the operation of said third motive means by said independently operable means when said third motive means has driven said scanning switches off normal position in response to signals on said communication channel, means including said scanning switches for selecting the active contact group during the first step of said scanning switches off normal position, means operable during operation of said third motive means initiated by signals on said communication channel at a predetermined step in the scanning switch cycle for interconnecting said data storage apparatus and selected contact group with the motive means corresponding to said selected contact group for driving the associated group of cam surfaces to a posi-

tion characterizing the entries in said data storage apparatus, and means operable during a succeeding step of scanning switch operation to clear the entries from said data storage apparatus.

4. In data translation apparatus, a group of jointly movable cam surfaces, first and second sets of contactors actuated by movement of said cam surfaces, data storage means, a communication channel, means alternatively connecting said data storage means and said first set of said contactors with said communication channel, motive means drivingly connected with said cam surfaces, means connecting said data storage means with said motive means through said second set of contactors whereby said cam surfaces are driven to a position corresponding to the information content of said data storage means, and means for energizing the members of said first set of contactors during the period of their connection with said communication channel.

5. In data translation apparatus, a group of jointly movable cam surfaces, first and second sets of contactors actuated by movement of said cam surfaces, data storage means, a communication channel, means alternatively connecting said data storage means and said first set of contactors with said communication channel, motive means drivingly connected with said cam surfaces, means connecting said data storage means with said motive
